(57) **CLAIM**

The ornamental design for a control device, as shown and described.

DESCRIPTION

FIG. 1 is a front perspective view of a control device showing our new design;

FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 is an enlarged view of a button of FIG. 1;

FIG. 8 is an enlarged view of a button of FIG. 2;

FIG. 9 is an enlarged view of a button of FIG. 4;

FIG. 10 is an enlarged partial view of the faceplate of FIG. 1;

FIG. 11 is an enlarged partial view of the faceplate of FIG. 2;

FIG. 12 is an enlarged view of the faceplate of FIG. 4;

FIG. 13 is an enlarged view of the faceplate of FIG. 6;

FIG. 14 is a front perspective view of a second embodiment thereof;

FIG. 15 is a front view thereof;

FIG. 16 is a left side view thereof;

FIG. 17 is a right side view thereof;

FIG. 18 is a top view thereof;

FIG. 19 is a bottom view thereof;

FIG. 20 is a front perspective view of a third embodiment thereof;

FIG. 21 is a front view thereof;

FIG. 22 is a left side view thereof;

FIG. 23 is a right side view thereof;

FIG. 24 is a top view thereof;

FIG. 25 is a bottom view thereof;

FIG. 26 is a front perspective view of a fourth embodiment thereof;

FIG. 27 is a front view thereof;

FIG. 28 is a left side view thereof;

(Continued)

FIG. 29 is a right side view thereof;
 FIG. 30 is a top view thereof; and,
 FIG. 31 is a bottom view thereof.

The broken lines illustrate structure or features which form no part of the claimed design.
 In FIGS. 7-13, the broken lines identify enlargements.
 The enlargements of FIGS. 7-13 also apply to the embodiments illustrated in FIGS. 14-31.

1 Claim, 23 Drawing Sheets
